UNITED STATES PATENT OFFICE.

JOHN HENRY WHITEHEAD, OF APPERLEY BRIDGE, AND ALFRED ROBERT WHITEHEAD AND WILLIAM EDWARD LAYLAND, OF LEEDS, ENGLAND.

CIRCULAR COMBING-MACHINE.

SPECIFICATION forming part of Letters Patent No. 741,088, dated October 13, 1903.

Application filed June 30, 1903. Serial No. 163,671. (No model.)

To all whom it may concern:

Be it known that we, JOHN HENRY WHITEHEAD, residing at Apperley Bridge, and ALFRED ROBERT WHITEHEAD and WILLIAM EDWARD LAYLAND, residing at Leeds, in the county of York, England, subjects of the King of Great Britain and Ireland, have invented a new and useful Improvement in Circular Combing-Machines, of which the following is a specification.

The object of this invention is to enable the small comb-circles of that type of combing-machines known as "Noble's circular combing-machines" to be removed and replaced, which is often necessary and desirable, without it being necessary, as at present, to take down the pillars carrying the top driving-shaft and the dabbing-motions and other attachments, which, besides being costly in the labor entailed, requires a considerable time, during which the output from the machine is completely lost to the mill owner. This object we attain by a new combination and arrangement of parts of such machine and a new construction of other parts, all of which are hereunder described with reference to the accompanying drawings, in which—

Figure 1 is a vertical section of a machine embodying our invention, taken on the line B B of Fig. 2 except in the neighborhood of the comb-circle, where the section is on the line A A of the latter figure, Fig. 2 being a plan on line C C of Fig. 1. Fig. 3 is a vertical section, to a larger scale, across one of the small comb-circles; and Fig. 4, an elevation at right angles to Fig. 3. Fig. 5 is a plan, looking upward, of the gearing-plate; and Fig. 6, a vertical section of the same on line D D of Fig. 5.

a a are the pillars carrying the top driving-shaft b, with pulleys c, and the brackets carrying the dabbing-motions, the latter not shown. These pillars are mounted upon the cross-bar d, but outside of instead of as hitherto within the small comb-circles e e. f indicates the large comb-circle.

g g are the noil-shoots, into which the noil is discharged, and these we place within instead of as hitherto without the small comb-circles e e. As the noil now requires to be

thrown off to the inside of instead of to the outside of the small comb-circles, we make the throwing-off knives h (see Figs. 3 and 4) to successively decrease in height from the outer to the inner sides of the small comb-circles. In order to accommodate this altered combination of pillars a a, small comb-circles e e, and noil-shoots g g and to still allow of the gearing-plate i being readily planed or turned, we form the gearing-plate as two diametrically opposite ring-surfaces joined diagonally across, (see Fig. 5,) so as to leave recesses (marked j) for the lower ends of the noil-shoots, and we support it by curved feet k, cast in one with it and extending circularly the full length of the said ring-surfaces. It will be evident that this combination as described allows the small comb-circles to be taken off the machine and replaced without taking down the dabbing-motions, top cross-shaft, and the pillars or the vertical gearing-shafts l, driving the gearing n, which pass down the pillars a a, being driven from the top cross-shaft b, and the construction of the gearing-plate i as described allows of the noil-shoots g being readily withdrawn, which is necessary to enable the small comb-circles e e to be withdrawn. The curved feet k also serve incidentally to prevent any wool getting from the sliver-bobbins into the gearing n.

m m are the fluted rollers guiding and driving the straightening-out or drawing-off leathers or bands.

n indicates the gearing for driving the comb-circles e e and f and the fluted rollers m from the vertical shafts l.

Having now particularly described and ascertained the nature and manner of carrying out our invention, what we claim as our invention, and desire to secure by Letters Patent, is—

1. In combing-machines of the type herein referred to, the combination of top cross-bar d, pillars a a mounted thereon outside the small comb-circles e e, and top driving-shaft b carried by said pillars a a, large comb-circle f, small comb-circles e e, to one side of said pillars a a respectively, noil-shoots g g within said small comb-circles e e, throwing-off knives h successively higher toward the outer

sides of the said small comb-circles, and gearing-plate *i* with recesses *j* and curved feet *k*, substantially as set forth.

2. In combing-machines of the type herein referred to, the combination of pillars *a a*, top horizontal driving-shaft *b*, small comb-circles *e e* respectively to one side of the pillars *a a*, large comb-circle *f*, noil-shoots *g g* within the small comb-circles *e e* respectively and throwing-off knives *h* successively higher at or toward the outer sides of the small comb-circles substantially as set forth.

3. In combing-machines of the type herein referred to the combination of gearing-plate *i* provided with integral supporting-feet and recesses for the upper ends of the noil-shoots, with the said shoots, the comb-circles and the driving-gear substantially as set forth. 15

JOHN HENRY WHITEHEAD.
